UNITED STATES PATENT OFFICE.

FREDERICK A. FRERICHS, OF PHILADELPHIA, PENNSYLVANIA, ASSIGNOR TO HORN & BRANNEN MFG. CO., OF PHILADELPHIA, PENNSYLVANIA, A CORPORATION OF PENNSYLVANIA.

DESIGN FOR AN ELECTRIC LANTERN.

Application filed April 14, 1925. Serial No. 13,121. Term of patent 7 years.

To all whom it may concern:

Be it known that I, FREDERICK A. FRERICHS, a citizen of the United States, residing at Philadelphia, in the county of Philadelphia and State of Pennsylvania, have invented a new, original, and ornamental Design for Electric Lantern, of which the following is a specification, reference being had to the accompanying drawing, forming part thereof.

Fig. 1 is a view showing my new design, the wide center panel being without ornamentation except at top and bottom as shown, and the two narrower side panels being ornamented as shown, it being under-

stood that the wide center panel is repeated on each of the four sides of the octagon, and that the narrow panels are repeated at the four diagonal corners of the octagon, the view as shown disclosing a side panel and two adjoining corner panels.

Fig. 2 is a diagrammatic view, on reduced scale, showing contour, in cross-section, taken through the center of the octagonal portion of the design.

I claim:

The ornamental design for an electric lantern, as shown and described.

FREDERICK A. FRERICHS.
